(57) **CLAIM**

The ornamental design for a “tab for pull-top can”, as shown and described.

DESCRIPTION

FIG. 1 is a perspective view of a tab for pull-top can which embodies my new and original design therefor, and wherein the dashed lines in the accompanying FIG. 1 represent the structural environment therefor forming no part of my claimed design,

FIG. 2 is an enlarged perspective view thereof;

FIG. 3 is a top plan view of thereof;

FIG. 4 is a bottom plan view thereof;

FIGS. 5 and 6 are right and left side elevational views thereof, respectively; and,

FIGS. 7 and 8 are front and rear side elevational views thereof, respectively.
